LIGHT DIFFUSORS FOR ILLUMINATING DEVICES

Edwin F. Guth, Sr., St. Louis County, Mo., assignor to The Edwin F. Guth Company, St. Louis, Mo., a corporation of Missouri

Filed Apr. 12, 1957, Ser. No. 652,499

9 Claims. (Cl. 240—78)

This invention relates generally to the control of light, and particularly to grids or lattices for use in connection with lighting fixtures and in other situations where it is desired to control light between the source thereof and the region upon which the illumination is desired.

In applicant's Patent No. 2,745,001, granted May 8, 1956, the lattice defines between the walls thereof a multiplicity of generally rectangular open spaces adapted to control the light from a suitable light source and passing through the lattice. Such lattice in the embodiments described is of a molded material.

In the construction of the patent, the cut-off angle of the light passing through any open space without diffusion is determined by the walls surrounding the open space and defining a planar aperture at the top and bottom thereof, so that the light passing directly through the aperture is restricted by the angle determined by the edges of opposite walls at the top and bottom.

One of the objects of this invention is to provide a lattice so constructed as to increase the light passing through the aperture beyond the normal cut-off angle of the wall at the entrance to the bottom of the opposite wall at the exit without introducing objectionable glare, or otherwise militating against the comfortable seeing conditions produced by the louver of the aforesaid patent.

Further objects will appear from the detail description in which will be described a number of embodiments of this invention; it is to be understood, however, that this invention is susceptible of various embodiments within the scope of the appended claims.

Generally stated, and in accordance with illustrative embodiments of this invention, the light controller comprises a lattice of light-transmitting material defining between the walls thereof a multiplicity of non-planar apertures which are formed to increase the cut-off angle for a limited amount of the light passing through the aperture. The structure is such as to variably increase such cut-off angle along the walls of individual apertures. While the cut-off may be in only one direction or in two opposite directions with respect to the area of the lattice, the cut-off may be in transverse directions with respect to the area of the lattice. In the illustrative embodiments, the above result is accomplished by varying the depth of at least some of the walls which bound an aperture and, particularly by reducing the depth transversely along the walls. In order to secure optimum results, the wall depths are reduced at spaced intervals around each aperture.

In the accompanying drawings:

Figure 1 is a perspective view of a luminaire provided with a light controller constructed in accordance with this invention;

Figure 2 is a face view of one embodiment of the light controller;

Figure 3 is a section on the line 3—3 of Figure 2;

Figure 4 is a section on the line 4—4 of Figure 2;

Figure 5 is an enlarged diagrammatical detail show-

2

ing the optical principles involved in the construction of Figures 2—4;

Figure 6 is a view similar to Figure 2, but showing another embodiment of this invention;

5 Figure 7 is a section on the line 7—7 of Figure 6;

Figure 8 is a section along the line 8—8 of Figure 6;

Figure 9 is an enlarged diagrammatical detail showing the principles involved in the embodiment, Figures 6—8;

10 Figure 10 is a view like Figure 3, but illustrating another embodiment of this invention;

Figure 11 is a view like Figure 3, but illustrating another embodiment of this invention; and

15 Figure 12 is a view like Figure 10, but showing another embodiment of this invention.

Referring to the accompanying drawings, and more particularly to Figure 1, 1 designates the fixture which may be supported in any suitable manner as in the ceiling 2 of a room. A frame 3 supports the light controlling 20 lattice indicated generally at 4 in any suitable manner, as in Patent No. 2,745,001. The fixture is provided with one or more lamps 5 which may be of a fluorescent type or of an elongated filament type supported in receptacles 6. These lamps are, therefore, in a position to direct 25 light on the top or entrance of the diffusing lattice to issue at the exits thereof. The fixture itself may be provided with reflectors (not shown) on the inside thereof to further direct the light on the lattice.

Referring first to Figures 2—4, and also to Figure 5, 30 the lattice has a series of walls 7 and 8 which define therebetween a multiplicity of open spaces 9 and whose edges define apertures 10 and 11, at the opposite faces of the lattice. The open spaces 9 are generally cubic, but at least one of the apertures, such as 10, being non-planar. To accomplish this, the edges of the walls 7 are recessed as shown at 12 at one face of the lattice to form spreading V-shaped valleys thereby reducing the height of the walls progressively from the corners of an aperture to a mid-point of its side. In other words, the edges are 35 configurated so that points therealong lie at varying distances from the center plane of the lattice, the configuration being repeated at each opening. As shown, the walls 7 are provided with a valley at opposite sides of each aperture.

40 Figure 5 illustrates the optical principles of the lattice of Figures 2—4. As an example, the walls 7 and 8 are $\frac{1}{16}$ inch thick and $\frac{1}{16}$ inch in height (vertical). The distance between the walls is $\frac{1}{16}$ inch. The depth of each valley 12 is $\frac{1}{16}$ inch. The cut-off angle for a beam 45 of light a, a' , passing adjacent the corner of aperture 10, is 45° to the horizontal. The cut-off angle is, however, gradually decreased from the corners of aperture 10 so that, at the apex of valley 12, it is about 35° to the horizontal. Thus, through each of the valleys 12 there 50 emerges a triangular pyramid of direct light in addition to that which would emerge through a planar aperture. The magnitude of this additional direct light, relative to the whole of the light transmitted, is insufficient to produce objectionable glare, but at the same time substantially improves the efficiency of the louver.

55 In the embodiment shown in Figures 2—4, the cut-off angle will be decreased beyond the normal cut-off angle in one dimension of the lattice, viz., in the dimension parallel with the line 3—3 in Figure 2.

60 In the form shown in Figures 6—9, both cross walls 65 are recessed at edges defining one face of the lattice to increase the cut-off angle in transverse directions, with respect to the area of the lattice. This is accomplished by forming the walls 8 with valleys 13 in addition to the valleys 12 in walls 7. Figure 9 shows the optical principle 70 of this construction which is similar to that in Figure 5, so that the same reference numerals are applied. In this embodiment, therefore, both walls are reduced in

depth at spaced intervals around each aperture. This construction is of advantage where the lattice forms a large part of the ceiling of a room so as to be directly over, back and front, and left and right, of the person or object illuminated.

Figure 10 shows an embodiment in which the walls 8 are reduced by curved indentation 14 instead of by two lines forming a V-shaped valley. The operation is, however, substantially that of the construction shown in Figures 5 and 9. In Figure 11, the construction is the same as that shown in Figures 2-5 except that walls 7 of the lattice are increased in vertical depth by V-shaped projections 15. This neutralizes the effect of valley 12 as to light rays from point sources directly in line with vertices of projection 15 and valley 12, and further modifies the character of the light passing through the louver. Obviously, the projections 15 may be provided on one or both of walls 7 and 8.

In Figure 12, the construction is like that of Figure 10 except that wall 8 is increased in depth by providing 20 arcuate projections 16. It will be understood that the projections 16 may be provided on both of walls 7 and 8.

The light controller may be constructed in any suitable manner, but as a practical embodiment, it is molded of a plastic light-transmitting material. The material may be glass or one of the transparent resins, such as methyl-methacrylate or polystyrene, clear or frosted. Such synthetic resins lend themselves readily to molding under pressure in a sectional mold in which the mold surfaces can be highly polished. Likewise, although glass is more difficult to press in large areas than synthetic resins, the lattice can be made of an area which lends itself to pressing and the glass may then be annealed in any suitable manner. The pressing may be done in sectional molds of a character used in the making of artificial cut glass trays and bowls. Likewise, a synthetic resin, such as Lucite, may be pressed in sectional molds of the character employed in making taillight reflectors for automobiles. Sections of the lattice may be placed end to end and side to side to form an area of any desired extent. In such a case, the projecting ends 20 of two lattices will form complete apertures.

Having thus described the invention, what is claimed and desired to be secured by Letters Patent is:

1. A light controller, comprising, a lattice of light-transmitting material formed by a series of parallel walls intersecting another series of parallel walls perpendicular to the first series, the edges of said walls collectively defining opposite faces of the lattice, the walls defining a multiplicity of open spaces therebetween and the edges of the walls defining apertures at the opposite faces of the lattice, the aperture-defining edges of parallel walls being of a serpentine configuration repeated from aperture to aperture so that points therealong are at varying distances from a virtual surface midway between said opposite faces of the lattice, thereby to produce a varying light cut-off effect across each opening of the lattice.

2. A light controller as set forth in claim 1, wherein the points along said serpentine edges closest to said virtual surface are located centrally between the walls 60 which intersect said serpentine-edged walls.

3. A light controller as set forth in claim 1, wherein the points along said serpentine edges most remote from said virtual surface are located centrally between the walls which intersect said serpentine-edged walls.

4. A light controller as set forth in claim 1, wherein all parallel walls have the same edge configuration.

5. A light controller as set forth in claim 1, wherein all walls have the same edge configuration, all walls being spaced from one another a uniform distance.

6. A light controller, comprising a lattice of light-transmitting material formed by a series of parallel walls intersecting another series of parallel walls perpendicular to the first series, the edges of said walls collectively defining opposite faces of the lattice, the walls defining a multiplicity of open spaces therebetween and the edges thereof defining apertures at the opposite faces of the lattice, the aperture-defining edges on one face of the lattice having a repeated indented edge configuration such that the points thereof at said intersection lie at a maximum distance from a virtual surface midway between said opposite faces of the lattice, whereas the points of said edges centrally between said edges lie at a minimum distance from the center plane of the lattice.

7. A light controller as set forth in claim 6, wherein the aperture-defining edges at the other face of the lattice all lie in a common plane.

8. A light controller, comprising, a lattice of light-transmitting material formed by a plurality of intersecting walls whose edges define the opposite faces of the lattice, the walls defining a multiplicity of open spaces therebetween and the edges of the walls defining apertures at the opposite faces of the lattice, the aperture-defining edges of parallel walls being of a serpentine configuration repeated from aperture to aperture the serpentine configuration being in a direction such that points therealong are at varying distances from the center plane of the lattice and the points along said serpentine edges closest to the center plane of the lattice are located centrally between the walls which intersect said serpentine-edged walls, thereby to produce a varying light cut-off effect across each aperture of the lattice.

9. A light controller, comprising, a lattice of light-transmitting material formed by a plurality of intersecting walls whose edges define the opposite faces of the lattice, the walls defining a multiplicity of open spaces therebetween and the edges of the walls defining apertures at the opposite faces of the lattice, the aperture-defining edges of parallel walls being of a serpentine configuration repeated from aperture to aperture the serpentine configuration being in a direction such that points therealong are at varying distances from the center plane of the lattice, and the points along said serpentine edges most remote from the center plane of the lattice are located centrally between the walls which intersect said serpentine-edged walls, thereby to produce varying light cut-off effects across each aperture of the lattice.
